US00D592556S

(12) **United States Design Patent**
Mehra

(10) **Patent No.:** **US D592,556 S**
(45) **Date of Patent:** ** *May 19, 2009

(54) **ALL-TERRAIN VEHICLE**

(75) Inventor: **Rajinder Mehra**, Johanneshov (SE)

(73) Assignee: **Husqvarna AB**, Huskvarna (SE)

(57) **CLAIM**

The ornamental design for all-terrain vehicle, as shown and described.

DESCRIPTION

FIG. 1 is a first side elevation view of a new design of an all-terrain vehicle;

FIG. 2 is a second side elevation view of the all-terrain vehicle;

FIG. 3 is a top view of the all-terrain vehicle;

FIG. 4 is a front view of the all-terrain vehicle;

FIG. 5 is a rear view of the all-terrain vehicle; and,

FIG. 6 is a perspective view of the all-terrain vehicle.

The portions shown in broken lines form no part of the claimed design.
